UNITED STATES PATENT OFFICE

FRANK J. KAHN, OF NEW YORK, N. Y.

LAUNDRY IRONER

Application filed November 15, 1929. Serial No. 407,434.

This invention relates to laundry ironers and more particularly with regard to its more specific features to presses in which the work is carried forward beneath rolls and is then returned beneath the steam chest by traveling belts.

It is an object of this invention to provide a device of the character described which may be easily released after ironing, to prevent scorching of the rolls or apron, but which may be quickly and easily adjusted to ironing conditions with a proper pressure and tension on the rolls and aprons.

It is a further object to produce a device in which the roll pressure and apron may be adjusted, each independent of the other, and each automatically.

In devices of this character, there is provided a steam chest which is so hot that it is not desirable to leave the apron and rolls in contact with it lest the apron and the covering on the rolls be scorched. It is desirable therefore to raise the rolls and slacken the apron away from the chest whenever the machine is brought to rest.

While, therefore, the apron and roll are moved at the beginning and again at the end of the ironing period, it is not satisfactory to attempt to operate them by a single control mechanism because with different conditions of heat, moisture and use, the apron changes in length without corresponding changes in the position of the rolls, and for different conditions of use it is desirable to vary the pressure of the rolls without altering the apron tension.

It is a further object of this invention, therefore, to provide a machine of the character described, in which each of these elements may be independently adjusted to its proper point, without having an effect upon the other, but in which both adjustments may be made simultaneously with a minimum of effort.

It is a further object to produce a device of the character described in which the apron tension and roll pressure may be each independently applied or relieved by power, but in accordance with which the degree of tension, pressure or release is controlled auto-

matically. This is specifically accomplished in the present embodiment by disconnecting the power mechanism from the control device when the desired degree of tension or pressure or release is obtained.

It is a further object to produce a device of the character described which will be simple in construction and rugged and reliable in operation.

Other objects of the invention will in part be obvious and will in part appear herein-after.

The invention accordingly comprises the features of construction, combinations of elements, and arrangement of parts, which will be exemplified in the construction hereinafter set forth and the scope of the application of which will be indicated in the claims.

For a fuller understanding of the nature and objects of the invention reference should be had to the following detailed description taken in connection with the accompanying drawings, in which:

Figure 1 is a fragmentary side elevation of a press embodying this invention.

Figure 2 is a rear elevation of a portion of the operating mechanism.

Figure 3 is a sectional plan along the lines 3—3 of Figure 1, parts being shown slightly out of position for greater clarity.

Figure 4 is a section on the line 4—4 of Figure 3.

Figure 5 is a fragmentary side elevation showing the control levers.

Figure 6 is a fragmentary view showing the lever centering device.

Figure 7 is a fragmentary view on the line 7—7 of Figure 6, showing the lever control detents and their operating mechanism.

Figure 8 is a section on the line 8—8 of Figure 7.

In the drawings the numeral 1 designates a steam chest preferably having concavities 2 in which fit the ironing rolls 3. These latter may comprise steel or iron rolls having a fabric covering supported from the roll surface by springs or other padding.

The rolls 3 are journaled in blocks 4 carried by a frame 5 which may be raised and lowered to raise or lower the rolls together.

The rolls are driven simultaneously and at the same speed by a common driving mechanism, not shown.

The undersurface 6 of the steam chest is smooth and inclined downwardly from each end toward the center, and a travelling apron 7 is held in contact therewith by a plurality of guide rolls such as 8, 9 and 10.

A second apron 11 is held in contact with the lower stretch of the apron 7 by guide rolls such as 12 and 13. Certain of the guide rolls are omitted for the sake of clarity. The rolls 8 and 12 are carried by a bracket 14 pivoted at 15. The position of the brackets is determined by a roll 16 upon a bracket cooperating with a cam 17, one such bracket roll and cam being provided at each side of the machine.

The cams 17 are keyed to the opposite ends 20 of a transverse shaft 18 which may conveniently be journaled in a hollow shaft 19 which may in turn be journaled transversely in the main frame 20 of the machine.

The shaft 18 may be driven from the power mechanism by the following train of mechanism. Upon the shaft 18 is a worm wheel 21 meshing with a worm 22 on a short shaft 23. This short shaft is driven by gears 24, 25 and 26 from a shaft 27 which extends to the other end of the machine and is in turn driven by the gears 28, 29 from a shaft 30.

This shaft 30 has at one end a bevel gear 31 and at the other end a hand wheel 32, making it possible to operate the cam 17 either by hand, by means of the hand wheel, or by power through the bevel gear.

Upon the side of the machine carrying the shaft 27 there is transversely journaled a short, hollow shaft 33 driven from the power shaft 34 of the machine by a chain 35 and sprockets 36 and 37. An operating rod 38 extends into the hollow of the shaft and is splined to it to rotate with it by a spline 39 extending outwardly through slots in the hollow shaft.

A pair of bevel gears 40 and 41 are journaled on the hollow shaft 33 in position to mesh upon the opposite sides of the bevel gear 31. Each of the bevel gears 40 and 41 is slotted on the end of its hub adjacent to the spline 39, but these hubs are so spaced as to provide a neutral position between them for the spline.

The rod 38 carries at its outer end a spool 42 engaged by a yoke 43 in turn controlled by a rod 44 operated by a lever 45 pivoted to the main frame 20 at 46. By this construction the movement of the lever 45 to one side will cause the spline 39 to engage one of the bevel gears 40 or 41 to drive the cam 17 from the shaft 34 but it will either raise the bracket 14 to tighten the apron or lower it to slacken the apron dependent on the direction of movement of the lever 45.

65. The roll frame 5 is raised and lowered by

two pairs of operating rods, these rods being disposed at the opposite sides of the two ends of the frame. Two of these rods 47 at one end of the machine are each controlled by an eccentric 48 upon a shaft 49 journalled to the frame 20. The other two rods 50 are each controlled by an eccentric 51 upon the hollow shaft 19. The shafts 19 and 49 each carry a worm wheel 53 meshing a worm 54 upon a longitudinal shaft 55.

A mechanism for driving the shaft 55 from the power shaft 34 is provided, similar to that for driving the shaft 27. The description heretofore given need not, therefore, be repeated. The parts have been given corresponding characters in the drawings suffixed by the letter *a*. It will, of course, be understood that the stub shaft 33 may conveniently be placed on the opposite side of the machine from the shaft 33*a*.

The rollers 8 and 12 are journalled upon blocks 60—61 which are slidable upon the frame 14 under control of screws 62—63, so that when a new belt is installed it may be initially tensioned to correspond with its 90 companion.

Adjacent to the levers 45 and 45*a* are gages 164 and 165 which indicate the tension on the aprons and the pressure on the rolls respectively. These may be operated in any 95 convenient and well known manner but as the operating mechanism forms no part of this invention it is not here illustrated.

With the above construction it will be clear that upon starting the machine the 100 levers 45 and 45*a* may be moved to bring the rolls to pressure and the apron to tension as shown by the gages, and as each of these is independent of the other there is no need for misadjustment of one to bring the other to 105 proper value, such as results from attempting to operate both from a common control.

With the above construction the machine may be operated under the control of the attendant to bring the apron tension and roll 110 pressure to any desired value but it is preferable to provide a mechanism controlled by the tension and pressure respectively for separate operating means so that when the levers 45 and 45*a* are originally moved no further act on the part of the attendant is required to bring the tension and pressure to the proper values. This automatic mechanism will now be described.

It will be understood that the position of the bracket 14 is at all times fixed by the angular position of the shaft 18 and the position of the head 5 is at all times determined by the position of the shafts 19 and 49. The automatic mechanism, therefore, comprises 125 means controlled by the position of these shafts to disconnect the operating mechanism.

Referring now to the control levers 45 and 45*a* these each comprise a stub lever 60 or 130

60a pivoted at 46 to which levers 45 and 45a are articulated as at 61 and 61a. Each of the stub levers 60 and 60a has an extension 62—62a. A compression spring 63a extends between the extension 62a and the lever 45a and a tension spring 63 connects the lever 45 with the extension 62. In this manner it will be clear that the levers are forced outwardly away from each other as seen in Figure 5. Each of these levers moves in a slot 64—64a in a plate 65 attached to the main frame and is adapted normally to be retained in central position by a pair of arms 66 and 67 pivoted at 68 to the main frame and having toes 69 and 70 respectively which bear against the flanges of the spool 42a or 42b. Between the arms 66 and 67 is a block 71 against which the arms 66 and 67 rest at their innermost position while compression springs 72 and 73 carried upon the rod 74 bear against the outer faces of the arms 66 and 67 to urge them toward the faces of the block 71. With this construction it will be evident that a movement of the spool 42a or 42b to either side will move one of the arms 66 or 67 against the force of its compression spring so that the spool is urged back to its neutral position thereby carrying with it the corresponding lever.

Referring now to Figure 8 it will be seen that there are provided adjacent to the plate 65 detents 75, 76, 75a and 76a each of which is slidable in suitable guides and is depressed inwardly by springs 77, 78, 77a or 78a. Each of these detents is provided with an inclined face 79 or 80, 79a or 80a so that as either lever is pressed to the side it will force the corresponding detent out of its path until the lever passes beyond the detent whereupon the detent will be forced into the path of the lever to retain the latter in position. Extending through slots 82 in the detents 75 and 76 is a shaft 83 journaled in arms 84 attached to the main frame. A similar shaft 83a extends through the detents 75a—76a. Each of the detents carries a roller 85 bearing upon a cam 86 fixed upon the shaft 83. Upon the outer end of the shaft 83a there is provided a finger 87a in position to be engaged by a cam 88a upon the shaft 49. This cam 88a is adjustably fixed to a shaft 49 by means of a set screw 89.

These cams 86 are provided with projections 90 which, as the shaft 83 is rotated cause the detents 75—76 to be withdrawn from the path of the levers 45—45a so that these levers can be returned to neutral position by the arms 66—67 and the cams 88 and arms 87 are so designed and so set that this return occurs in the one direction when the rolls have attained a proper pressure, and in the other direction when the rolls are wholly free.

The detents 75 and 76 are similarly controlled by the shaft 83 save that in this in-

stance the corresponding arm 87 is controlled by a fork 92 mounted on a rod 93 reciprocated by a lever 94 the end of which 95 is engaged by the cam 88 on the shaft 18 in the same manner that the finger 87a is controlled by the cam 88a. 70

The slots 64 and 64a preferably each have a central notch 96—96a to retain the levers in central position.

By the above construction it will be seen that the roll pressure and apron tension may be easily adjusted by grasping the levers 45—45a with one hand and pressing them toward each other to release them from the central notches 96—96a. They may then be moved together to one side until they snap behind the appropriate detent. Thereupon the power mechanism operates the control mechanism for the rolls until the attainment of the predetermined pressure releases the detents 75a and 76a, permitting the handle 45a to snap back to central position. Similarly the attainment of a predetermined apron tension causes the withdrawal of the detents 75 and 76 and the lever 45 also to snap back to neutral. Thus the only operation required of the attendant is to move the control levers and leave them. The tension and pressure are thereupon controlled automatically.

Since certain changes may be made in the above construction and different embodiments of the invention could be made without departing from the scope thereof, it is intended that all matter contained in the above description or shown in the accompanying drawings shall be interpreted as illustrative and not in a limiting sense. 95 100

It is also to be understood that the following claims are intended to cover all of the general and specific features of the invention herein described, and all statements of the scope of the invention which, as a matter of language, might be said to fall therebetween. 105

Having described my invention, what I claim as new and desire to secure by Letters Patent, is:—

1. In a device of the character described having a plurality of rolls and an apron co-operating with a steam chest, in combination, means for raising and lowering the rolls and means for altering the apron tension, said two sets of means being independent of each other and having separate control means, said control means being situated adjacent to each other and movable in the same direction to lower the rolls and tension the apron. 115 120

2. In a device of the character described having a plurality of rolls and an apron co-operating with a steam chest, in combination, a power shaft, means for raising the rolls including a shaft journaled longitudinally of the machine, a reversing mechanism and a lever for connecting said longitudinal shaft to said power shaft through said reversing 125 130

mechanism, and means for slackening the apron independent of said roll raising mechanism, including a transverse shaft, a reversing mechanism and a lever for connecting said transverse shaft to said power shaft through said last named reversing mechanism.

3. In a device of the character described having a plurality of rolls and an apron co-operating with a steam chest, in combination, a pair of shafts journalled longitudinally of the machine, means for raising the rolls operatively connected to one of said shafts, means for slackening the apron operatively connected to the other of said shafts, a source of power and means for reversibly and independently connecting each of said shafts to the source of power.

4. In a device of the character described having a plurality of rolls and an apron co-operating with a steam chest, in combination, a pair of shafts journalled longitudinally of the machine, means for raising the rolls operatively connected to one of said shafts, means for slackening the apron operatively connected to the other of said shafts, a source of power, a reversing mechanism for each of said shafts and independent means for connecting said source of power to each of said reversing mechanisms.

5. In a device of the character described having a plurality of rolls and an apron co-operating with a steam chest, in combination, a roll raising mechanism including a frame, rods for supporting said frame, eccentrics for controlling the position of said arms, a shaft carrying a pair of said eccentrics, means for slackening the apron including brackets about which the aprons are trained, cams controlling the position of said brackets, a shaft carrying said cams, one of said shafts being hollow and the other being journalled in said hollow shaft.

FRANK J. KAHN.
